ELECTRIC SWITCH

Donald G. Kimball, Stratford, Conn., assignor to
General Electric Company, a corporation of New
York

Application April 13, 1938, Serial No. 201,786

4 Claims. (Cl. 200—6)

The present invention relates to electric switches, and more particularly to rotary switches having cam-actuated contacts and which are adapted for use with heater elements, or the like.

It is an object of the invention to provide an improved construction and arrangement in switches of this type in which the contact elements are completely enclosed and protected against the entrance of dirt and foreign substances and in which the mechanism is easily and quickly assembled within the housing.

In the accompanying drawings Fig. 1 is a side view of the switch; Fig. 2 is a side view in cross-section through the switch; Fig. 3 is a view along the line 3—3 of Fig. 2; Fig. 4 is a view along the line 4—4 of Fig. 2; Fig. 5 is a view along the line 5—5 of Fig. 2; Fig. 6 is a view along the line 6—6 of Fig. 2; Fig. 7 is an exploded view of the switch positioning mechanism; Fig. 8 is a diagrammatic view showing the switch in "off" position, and Figs. 9, 10 and 11 are diagrammatic views showing the switch in "high," "medium" and "low" positions, respectively.

Referring to the drawings, the electric switch of this invention is indicated generally at 10 and comprises a two-part casing formed of molded material, such as a phenolic condensation product and filler, with the upper part 11 closely engaging the lower part 12 to form a completely sealed-in housing for the switch mechanism. The parts of the housing are held in assembled relationship by means of metal straps 13 which surround the housing on all four sides and are riveted together at each end as shown at 14.

Extending through the casing is a non-circular shaft 15 which is rotatably supported by means of circular openings (not shown) formed in the front and rear walls of the casing. The rear portion of the shaft 15 extends through the casing and is provided with a split washer 16 disposed between the casing and a bent-up portion of the strap 13 to prevent axial movement of the shaft. The front end of the shaft is provided with an operating handle 17.

A plurality of operating cams 18, 19 and 20 are spaced longitudinally along the shaft 15 and are formed with appropriately positioned depressions to cooperate with a plurality of contact blades. The contact blades are supported from terminal members at one end and are provided at their other ends with silvered contacts which cooperate with corresponding contacts on other terminal members. The terminal members are located in pairs and a plurality of contact blades are provided to cooperate with the re-

spective cams to form a multi-contact switch mechanism.

Cooperating with the cam element 20 (Fig. 6) is a contact mechanism including a lower terminal element 21 which may be connected to one of the load lines and a corresponding upper terminal member 21' which may be connected to a heater element. The terminal member 21' is provided with a horizontally disposed flexible contact blade 22 provided at its end with a silvered contact point which cooperates with a corresponding contact point on the terminal element 21 to form a contact 23. The blade is provided with a depressed portion 24 which cooperates with the cam 20. The terminal member 21' is likewise provided with a depending contact blade 25 formed with a contact point at its outer end which engages a corresponding contact point on an adjacent terminal member 37 to form a contact 26. In order to cooperate with the cam 20 the contact blade 25 is formed with an extended portion 25'. The terminal element 21 is provided with an extension 27 which is secured to a baffle plate 28 by means of a hollow rivet 27'. Correspondingly, the terminal member 21' is provided with an extension 30 which is secured to the baffle plate 28 by a hollow rivet 31. The baffle plate 28 is disposed in grooves 29 formed in the upper and lower housing members 10 and 11, and thereby forms a chamber for the terminals 21 and 21', the contacts 23 and 26, and the cam element 20. A corresponding chamber is formed for each of the cam members 18 and 19 in which the cooperating terminals and contacts are placed.

Referring more particularly to Fig. 5, a second contact mechanism is provided including a terminal element 32 which may be connected to a load line and a corresponding terminal member 32' which may be connected to a heater element. The terminal member 32' is located centrally of the casing adjacent the terminal member 21' and is provided with an offset portion 33 bearing a spring contact blade 34 having a depressed portion 34' for engagement with the cam 19. The blade 34 carries a silvered contact point at its outer end which cooperates with a contact point formed on an extension 35 of the terminal element 32 to form a contact structure 36. The terminal element 32 is provided with a second extension 37 opposite the extension 35 having a silvered contact point cooperating with the contact on the blade 25 to form the contact structure 26 above described. The extended portion 37 of the terminal element 32 is bent at right angles to the terminal element and extends 35

through an opening 28' in the baffle plate 28 to form the contact 26, as best shown by Figs. 5 and 6. The terminal element 32 is secured to a second baffle member 38 by a hollow rivet 39 while the corresponding terminal element 32' is likewise secured to the baffle member by a hollow rivet 39'. The baffle member 38 cooperates with the walls of the casing resting in grooves 29 to form a second chamber which houses the cam element 19 and the contact structure 36 immediately adjacent the baffle plate 28.

The contact structure which cooperates with the third cam element 18 is best shown by Fig. 4, and comprises a terminal element 40 which may be connected to a load line and a corresponding terminal member 40' which may be connected to a heater element. The terminals extend through openings in the casing on opposite sides thereof adjacent the center terminals 32 and 32'. The terminal member 40' is provided with a longitudinally extending contact blade 41 provided at its outer end with a silvered contact point to cooperate with a corresponding contact point on the terminal element 40 thereby forming a contact structure 42. In order to engage the cam element 18, the contact blade 41 is provided with a depressed portion 41'. To secure the terminal element 40 to a baffle plate 44 the terminal element is provided with an extension 45 fastened to the baffle plate 44 by means of a hollow rivet 46. The terminal member 40' is provided with a depending arm 47 which is likewise secured to the baffle plate 44 by means of a hollow rivet 48.

It will be apparent that the respective terminals are secured to the baffle plates in such a manner as to form structures which may be inserted within the casing as units. To this end, the casing is provided with knock-out elements 49 which are punched out wherever a terminal is to extend and thereby the terminals are placed through the opening formed by the knock-out and the halves of the casing brought together to securely clamp the baffle plates 28, 38 and 44 in the slots 29 and thereby hold the terminals securely in position with the contact structures properly positioned for cooperation with the operating cams.

The terminal elements 21, 32 and 40 are each provided with clamping means comprising screws 50 which cooperate with arms 51. The arms are provided with arcuate ends 52 which may receive the load line wires and the other ends of the arms are bent at an angle and extend through openings 53 formed in the terminal elements. In this manner a highly effective securing means is provided which effectively maintains the load lines in electrical contact with the terminal elements. In order to secure a heater conductor or cable to the terminal members 21', 32' and 40', these members are each provided with securing means comprising screws 54 and the locking plates 55. The locking plates 55 are provided with indentations 56 which receive the heater cable and cooperate with the terminal members to clamp the cable.

The switch is provided with a positioning means which is disposed between the front wall of the casing and the baffle plate 44. This positioning means is best shown by Figs. 3 and 7 and comprises a plate 57 mounted upon the shaft 15 by means of an opening 58 contoured to the dimensions of the shaft. The plate 57 is provided with a plurality of diametrically opposed pins 59 which are seated within openings 60 forming part of the coil torsion springs 61. The ends of the 75 springs are provided with loops 62 which engage

a lug 63 formed on each of the opposed links 64. The links are provided with extending pins 65 and arms 66, the latter being provided with keyhole slots 67. Anti-friction rollers 65' are mounted on the pins. In the assembled relationship of the positioning means the pins 59 extend through the openings 60 forming part of the torsion springs and likewise extend through the keyhole slots 67 provided in the link arms 66. As shown more particularly in Fig. 3, the rollers 65' cooperate with indentations 68 formed in the front wall of the housing. The springs 61 bear against the lugs 63 and maintain the rollers 65' within the indentations 68. The indentations 68 are located in positions corresponding to that taken by the switch cams for the various positions of the switch. As the switch is rotated from one position to the other, rotation of the plate 57 will cause the looped ends of the springs to bear against the corresponding lugs 63, thereby pivoting the links 64 about one of the pins 59 so that the rollers 65' will ride up the side of the indentations 68 and snap over into the adjacent one. In this manner the switch cams are accurately located for all positions of the switch. 25

One use of the device is as a heater switch for controlling the heat to a plurality of resistance heaters H¹, H². In practice it may be desirable to place these heaters in an oven and to regulate the heat of the oven to three speeds such as 30 "high," "medium" and "low." Figs. 8 to 11 inclusive show the switch connected to the heaters H¹ and H² and to the load line which comprises a three-wire circuit including load wires L¹ and L² with a neutral wire N. Customarily, 110 volts 35 are applied on each side of the central neutral wire, although other voltages may be applied as occasion demands. The terminal elements 21 and 40 are connected to the outside load lines L² and L¹, respectively, and the terminal element 40' 40 is connected to the center neutral line N. The heater elements H¹ and H² are connected in series with a center tap connected to the center terminal member 32'. The other end of the heater H¹ is connected to the terminal 40' and the corresponding end of the heater H² is connected to the terminal member 21'. The various positions of the switch such as "off," "high," "medium" and "low" are shown by Figs. 8 to 11, respectively. It should be noted that the dwells 50 or recesses in the cams are properly positioned to operate the depressed portions of the respective contact blades to open and close the contacts thereby controlling the current to the respective heater elements H¹ and H² for the various positions of the switch. 55

In Fig. 8 the switch is shown in "off" position with the contacts 42, 36, 23 and 26 all open. In Fig. 9 the switch is shown in the "high" position and current is caused to flow from each of the load lines L¹ and L² to each of the heater elements and back through the central or neutral terminal member to the neutral line N. Current from the line L¹ passes through the terminal element 40, contact 42, heater element H¹, neutral terminal member 32', contact 36, and back to the neutral line N. Similarly, current from the line L² passes through terminal element 21, contact 23, heater element H², neutral terminal 32', contact 36 and back to the neutral line. Thus 70 the heater elements H¹ and H² are connected in parallel and are each subjected to a potential of 110 volts in the case where currents of that voltage are employed.

Turning the operating handle to the "medium" 75

position rearranges the contacts as shown in Fig. 10. In the "medium" position only one of the heater elements is employed, in this case the element H^1 . Current from the line L^1 flows through terminal element 40, contact 42, heater H^1 , terminal 32', contact 36 to the center or neutral line terminal 32. Current cannot reach the other heater element H^2 from the line L^2 because both the contacts 23 and 26 are maintained in open position by the cam element 20.

In the "low" position, shown by Fig. 11, the voltage across one line is applied to both the heater elements H^1 and H^2 connected in series. Current flows from the line L^1 through terminal element 40, contact 42, heater elements H^1 and H^2 , terminal 21', contact 26, and back to the neutral terminal 32. No current is applied through the medium of terminal member 21 because contact 23 is open and likewise the center or neutral terminal member 32' is disconnected from the circuit due to the opening of contact 36. It will be seen that a switch has been provided which permits the heater elements to be operated together to secure a "high," "medium" and "low" temperature.

By making the cam elements 18, 19 and 20 symmetrically shaped, it is possible to secure a switch which may be rotated throughout a complete revolution, and which is provided with an "off" position and three heat positions. By turning the handle clockwise, as shown in Figs. 8 to 11, and continuing the rotation of the handle past the point illustrated by Fig. 11, it will be apparent that the heating cycle will again occur in the order given, that is, "off," "high," "medium" and "low" because similar cam surfaces will be presented to the depressed portions of the contact blades. Furthermore, the switch may be operated in either direction with equal effectiveness. By providing a switch which is completely enclosed within a housing, the entrance of dirt, spillage, or foreign matter is prevented in those cases where the switch is employed in electric appliances such as an electric range. Moreover, by providing baffle plates between the respective terminals, chambers are provided which isolate the contacts one from the other, thereby preventing any possibility of short circuit between the various contacts. By mounting the terminal members upon the baffle plates, a compact and rigid structure is secured which is easily assembled by placing the halves of the casing over the respective terminals and disposing the terminals through the openings in the casing formed by the punched knock-outs. The assembled switch mechanism and housing is then held in completed form by the strap members 13.

What I claim as new and desire to secure by Letters Patent of the United States is:

1. In an electric switch, a housing, a plurality of baffle members disposed within said housing and forming adjacent chambers therein, a pair of terminal elements disposed in each of said chambers and connected to a corresponding baffle member, there being openings in said housing through which said terminal elements extend for connection to electrical circuits, contact means in each of said chambers for interconnecting the terminal elements of each pair, a shaft rotatably mounted in said housing and a cam disposed in each of said chambers for actuating said contact means, each of said cams being mounted on said shaft.

2. In an electric switch, a two-part housing comprising upper and lower portions, said portions being provided with spaced openings therein, a plurality of baffle plates seated in said housing, a plurality of terminal elements secured to said baffle plates, a plurality of contact means interconnecting pairs of said terminal members, said terminal members projecting through said openings for connection to electrical circuits, said terminal elements moving through said openings to extended position as the parts of said housing are moved together to closed position clamping said baffle plates whereby said contact means are sealed within said housing, means for securing the parts of said housing in closed position, and cam means cooperating with said contact structures for controlling the circuits.

3. In an electric switch, a two-part housing, each of said parts having an opening therein, a baffle element mounted in said housing and forming a chamber therein, terminal elements disposed in said chamber and secured to said baffle member, said terminal elements extending through the openings in said two-part housing for connection to electrical circuits, contact means adapted to interconnect said terminal elements, and a cam means for operating said contact means.

4. In an electric switch, a two-part housing, each of said parts having an opening therein, a baffle element adapted to be mounted in said housing to form a chamber therein, terminal elements secured to said baffle member, said terminal elements extending through the openings in said two-part housing for connection to electrical circuits, said two-part housing being placed over said terminal elements and being secured together to clamp said baffle element thereby forming a chamber in said housing, contact means secured to said terminal elements and disposed in said chamber, a cam means for operating said contact means, and means for holding said two-part housing in closed position to provide a completely enclosed switch.

DONALD G. KIMBALL.
